UNITED STATES PATENT OFFICE.

RALPH T. CHEESEMAN, OF LYNN, MASSACHUSETTS, ASSIGNOR TO GENERAL ELECTRIC COMPANY, A CORPORATION OF NEW YORK.

ELECTRIC-ARC DEVICE.

Application filed March 24, 1921. Serial No. 455,257.

To all whom it may concern:

Be it known that I, RALPH T. CHEESEMAN, a citizen of the United States, residing at Lynn, in the county of Essex, State of Massachusetts, have invented certain new and useful Improvements in Electric-Arc Devices, of which the following is a specification.

The present invention relates to electric arc devices in which an arc operates in a gas between electrodes of refractory material which are heated to incandescence during operation but are otherwise substantially unaffected by the arc. My invention particularly relates to the starting of an arc between nonconsuming electrodes separated by a fixed gap.

In Patent 1,310,067 issued on July 15, 1919, to Philip K. Devers, is described a lamp having tungsten electrodes between which an arc is operated in mercury vapor. Ionized vapor is generated preliminary to starting the arc, by an heater dipping into a pool of mercury, or an amalgam. In the Dever's device the ionizing circuit is opened in response to current flow therein after a predetermined time interval has elapsed. In case the arc has not started by that time, the ionizer is again connected in circuit and the starting cycle is repeated.

As a result of my present invention, a simplified starting mechanism is provided in which the ionizer remains continuously in circuit until an arc has started and is deenergized in response to flow of energy in the arc circuit. Among the novel features of my invention is an arrangement for impressing at starting a high voltage upon the electrodes of each device, independently of other devices, and automatically reducing this voltage when the arc has started.

The accompanying drawing illustrates an embodiment of my invention as applied to the starting of an incandescent arc lamp.

Referring to the drawing, the arc lamp illustrated comprises an elongated envelope 1 into which are sealed conductors 2, 3, tipped by stems 4, 5, to which are connected electrodes 6, 7, of refractory metal such, for example, as tungsten. Immediately below the electrode 6, 7, is located a globule 8 consisting of mercury, or an amalgam. Dipping into the mercury is a wire 9 connected to the stem 5 and to the leading-in conductor 10. Preferably a gaseous filling is pro-

vided in the bulb 1, for example, argon at a pressure of about 20 to 40 c. m. of mercury.

Electric current is supplied by a transformer 12, (in this case an auto-transformer), the primary circuit of which is connected by the conductors 13, 14, to an alternating current supply circuit 15. The auto-transformer is provided with a high voltage winding 16, the free terminal of which is connected by the conductors 17, 18, to the electrode 6, both in series with the magnet winding 19 and with the mercury body in the mercury switch 20, which, when no current is flowing is in contact with the terminals 17', 18'. The electrode 7 is connected by a conductor 21 to a point of intermediate potential on the primary winding 12.

The mercury switch 20 is provided with a third terminal 22 connected by a conductor 23 to a point of intermediate potential of the autotransformer, whereby current from the transformer section between the conductors 23 and 21 operating as secondary may be conveyed. When the switch 24 is closed, current traverses the ionizer 9, heating the same to incandescence. Mercury is vaporized and ionized by contact with the incandescent wire. As a high voltage is impressed on the electrodes 6, 7, namely, the voltage between the points of connection on the transformer of the conductors 17 and 21, an arc is readily started between the electrodes 6, 7.

When the arc-sustaining current traverses the coil 19, the core 25 is pulled up tilting the switch 20, which is pivotally supported at 26. The mercury runs into the bent arm 27, completing a circuit through a contact 22 to the transformer by the conductor 23 and breaking contact with the terminal 17'. As a result the circuit connection of the electrode 6 is shifted from the high voltage taps to the low voltage taps between the conductors 21 and 23. Preferably contact of the mercury with the terminal 22 is made before contact with 17' is broken. The coil 27 in circuit with the conductor 23 being now traversed by current, the mercury switch is held in the running position which leaves the conductor 17 and the coil 16 disconnected from the arc device. The arc will continue to operate at low voltage when the electrodes have been heated to incandescence, current being supplied by the

transformer section between the conductors 17 and 23 which constitutes a low voltage secondary.

When the arc current begins to flow and core 25 is pulled upward the double-pole switch 30 in circuit with the conductors 31, 32, connected to the ionizer 9 is opened, thereby deenergizing the heater.

It will be observed that the deenergizing 10 of the ionizer and the shifting of the arc from a high voltage to a low voltage is accomplished by a simple movement of a magnet. The described device is suitable for series or multiple circuit operation. For 15 the purpose of illustration a second set of lamp connections has been indicated connected to the same supply conductors.

What I claim as new and desire to secure by Letters Patent of the United States, is:—

20 1. An electric arc apparatus comprising an electric arc device, circuit connections for delivering current which is capable of starting and operating an arc between said electrodes in the presence of ionized vapor, 25 means within said lamp for furnishing ionized vapor to the space between said electrodes, an electric circuit for supplying said device with current at lower potential, and means responsive to flow of current between 30 said electrodes for transferring the connections of said device to said lower potential circuit, said means being adapted to break the circuit of higher potential after the circuit of lower potential has been established.

35 2. An electric arc apparatus comprising an arc device containing electrodes adapted to operate at incandescence, separate means therein for furnishing ionized vapor to the space between said electrodes, a source of 40 current having both low potential and high potential windings, connections to said electrodes from the high potential winding, a connection between the low potential winding and said ionizing means, and electro- 45 magnetic means responsive to current flow between said electrodes for disconnecting said ionizing means and shifting connections to said electrodes from the high potential to the low potential winding.

50 3. An electric arc system comprising the combination of a gas-filled arc device having refractory electrodes separated by a fixed gap, a transformer having a high potential winding and a low potential winding, said windings being initially connected in series to said electrodes, means for starting a discharge between said electrodes, and means responsive to flow of current between 55 said electrodes for changing connections to supply said electrodes exclusively by said low potential winding.

4. An electric arc system comprising the combination of an arc device having electrodes separated by a fixed gap and adapted 60 to operate at incandescence, a transformer

connected to supply said electrodes with current, means for starting an arc between said electrodes, and electromagnetic means responsive to flow of current between said electrodes to both deenergize said starting 70 circuit and to materially lower the potential of the current supplied from said transformer.

5. An electric arc system comprising the combination of an arc device having electrodes separated by a fixed gap, current supply means therefor having circuit connections to points of different potential, an electromagnet having an operating winding and a holding winding respectively responsive 80 to current flow between said electrodes, means for initiating an arc between said electrodes and a switching means controlled by said magnet for altering current connections to said arc device from said supply 85 means to lower the impressed potential when the arc has started and to energize said holding winding whereby the lower potential connection is maintained.

6. An electric arc apparatus comprising 90 an enclosed arc device having electrodes normally out of contact with each other, means for supplying current at a voltage higher than the normal operating voltage of an arc between said electrodes, means for starting an arc between said electrodes, a switch for changing connections of said device to said source to lower the voltage to a normal operating value, a second switch for deenergizing said starting means, and means 95 responsive to current flow between said electrodes for operating both of said switches.

7. An electric arc apparatus comprising the combination of an arc device having refractory electrodes operating in a gas at 100 substantial pressure, a source of current, circuit connections between the electrodes of said arc device and said source, means for ionizing the gas filling in said device, and means responsive to current operating an 105 arc in said device for deenergizing said starting means and for rearranging the connections to said source to lower the voltage applied to said electrodes.

8. An arc system comprising the combination of an arc device containing a starting means, a transformer provided with taps for furnishing current at different voltages, circuit connections between said starting means and low voltage taps of said transformer, a second set of connections from the electrodes of said device to taps of higher voltage, and electromagnetic means responsive to current flow between said electrodes for deenergizing said starting means and also shifting the electrode connections from the high voltage taps to the low voltage taps while keeping an arc between said electrodes in operation.

9. An arc system adapted for the opera- 110

- tion of arc devices having refractory electrodes and an ionizing circuit which comprises the combination of a transformer having low voltage and high voltage windings, circuit connections from the high voltage windings to said electrodes, a mercury switch having contacts whereby the connections from arc electrodes may be shifted from a high voltage winding to a low voltage winding, an electromagnet responsive to arc current for operating said switch and a second switch also operated by said electromagnet for opening said ionizing circuit when said mercury switch is operated.
- 10 10. An arc system which is adapted for the operation of an arc between electrodes remaining normally out of contact with each other comprising the combination of a transformer having both a low voltage winding and a high voltage winding, circuit connections from said windings to said electrodes, a separate circuit for starting said arc, electromagnetic means for opening said starting circuit in response to current in the arc circuit and a mercury switch operatively connected to said electromagnetic means and having a set of contacts in said high voltage
- 15 circuit and a set of contacts in said low voltage circuit, the mercury filling in said switch being operative to shift circuit connections from one set of contacts to another while maintaining the continuity of current supply.
- 20 11. An arc system comprising a transformer having a plurality of taps, an ionizing circuit connected to a pair of said taps, an arc starting circuit connected to taps of higher potential, a mercury switch having contacts which, when bridged, will complete both of said circuits, a third circuit connected to taps of low potential on said transformer and including a third terminal in said switch to which contact is made when the other contacts are opened, an electromagnet responsive to current in the arc starting circuit for operating said mercury switch and a cut-out in said ionizing circuit which is opened by the operation of said electromagnet, said mercury switch being constructed to close the third circuit before the arc starting circuit is opened.
- 25 In witness whereof, I have hereunto set my hand this 17th day of March, 1921.
- RALPH T. CHEESEMAN.
